L. L. ROSENFIELD

Des. 104,880

GAITER OR SIMILAR ARTICLE

Filed April 16, 1937

*Inventor:
Lewis L. Rosenfield,
by Walter E. Lombard, Atty.*

UNITED STATES PATENT OFFICE

104,880

DESIGN FOR A GAITER OR SIMILAR ARTICLE

Lewis L. Rosenfield, Mattapan, Mass.

Application April 16, 1937, Serial No. 68,824

Term of patent 7 years

To all whom it may concern:

Be it known that I, Lewis L. Rosenfield, a citizen of the United States, residing at Mattapan (Boston), in the county of Suffolk, State of Massachusetts, have invented a new, original, and ornamental Design for a Gaiter or Similar Article, of which the following is a specification, reference being had to the accompanying drawing, forming part thereof.

The drawing represents a side elevation of the article showing my new design.

I claim:

The ornamental design for a gaiter or similar article, as shown.

LEWIS L. ROSENFIELD.
